UNITED STATES PATENT OFFICE.

OSCAR AUGUST SMITH, OF EAST CLEVELAND, OHIO; THE CLEVELAND TRUST COMPANY ADMINISTRATOR OF SAID OSCAR A. SMITH, DECEASED.

PRIMING CUP.

Application filed July 17, 1924. Serial No. 726,475.

To all whom it may concern:

Be it known that I, OSCAR A. SMITH, a citizen of the United States, residing at East Cleveland, in the county of Cuyahoga and State of Ohio, have invented certain new and useful Improvements in Priming Cups, of which the following is a specification.

This invention relates to priming cups for 10 gas engines or motors, an object thereof being to provide an improved gasoline priming cup simple in construction, durable in use, readily operated, and which can be manufactured at a minimum of expense, the 15 primary object of the invention being to provide a priming cup of reduced size with a gasoline receiving or cup chamber of increased capacity.

The present improved priming cup is an 20 improvement in part upon that shown and described in my prior Patent No. 1,440,844 dated January 2, 1923. In that patent in order to obtain a cup chamber of large capacity it was necessary to make the entire 25 article of comparatively large size.

In the present improvement the article is materially reduced in size as compared with that shown in said patent while the chamber or cup portion thereof however, is 30 materially increased in size, thereby giving an equal or larger capacity to the cup chamber than was possible in the priming cup of the patent referred to. Thus I am able to obtain a small priming cup having a chamber of greater capacity than heretofore, thus enabling the article to be made much cheaper since there is a considerable saving of material in the manufacture of the article, and therefore the cup can be sold much cheaper.

40 In other words, in the present improvement the cost of production is materially decreased without in any way decreasing the capacity of the gasoline chamber or cup portion.

In the drawings accompanying and forming a part of this specification, Fig. 1 illustrates a side view of one form of this improved cup; Fig. 2 is a vertical sectional view thereof; Fig. 3 is a top view; Fig. 4 is a side view of another form thereof; and 45 Fig. 5 is a vertical sectional view of the construction shown in Fig. 4.

Similar characters of reference indicate corresponding parts in the several drawings.

50 Before explaining in detail the present improvement and mode of operation thereof, I

desire to have it understood that the invention is not limited to the details of construction and arrangement of parts which are illustrated in the accompanying drawings, since the invention is capable of other 60 embodiments, and that the phraseology which I employ is for the purpose of description and not of limitation.

In the preferred form thereof herein shown and described this improved priming cup, which is adapted for various purposes, comprises a body member 10 consisting of a chambered and interiorly threaded nut portion 11 having a threaded projection or stem 12 to permit the device to 70 be attached to the cylinder head of the engine. This body member is provided on the interior thereof with a tapered part 13 for seating the lower end of the cup proper, the nut portion being provided with interior threads 14 above the seat. Screwing into the nut portion of the body member is a cup member 15 having an exteriorly threaded projection or stem 16 cooperating with the interior threads of the body member. 75 This threaded portion 16 is chambered as at 17 and together with the enlarged chamber 18 above it forms the gasoline receiving chamber or cup proper of the device.

80 Secured to the bottom wall of the chamber portion 17 as by heading it therein is a valve stem 19, of less diameter than the bore 23' of the body, carrying a valve 20 and the bottom wall of the chamber 17 is 85 provided with openings shown as two in number 25 for the passage of the gasoline to the cylinder when the valve is open.

The construction so far described applies to both forms of priming cups shown. In 90 the forms shown in Figs. 1 and 2 however, the stem 19 has its valve 20 opening in the direction of the flow of the fluid, this valve being tapered so as to seat against the lower edge 21 of the body stem. In the form 100 shown in Figs. 4 and 5 the valve stem is also provided with a tapered valve, seating however, in the direction of the flow of the fluid and fitting against the edge of an opening 21' of the valve body stem which is flanged 105 or turned for this purpose as at 22'.

In the present improvement it will thus be observed that the cup screws into the body instead of on to the body as shown in my prior patent referred to, and that the 110

cup together with its bottom wall is constructed as one integral member instead of, as shown in two parts in my patent referred to. As a result of these differences in construction the priming cup can extend down into the threaded portion of the cup proper, thus increasing the capacity of the cup without requiring the article to be made of larger size.

- 5 10 In other words, due to the fact that the cup screws into the body instead of on to the body, which permits the capacity of the cup to be materially increased, the entire article can be made of much smaller size than that shown and described in my patent referred to, and consequently the article can be produced at less cost and therefore sold much cheaper. The cup portion is provided with an external knurled portion 26 to facilitate 15 the opening and closing of the cup and it will be observed that when the body member is screwed into the engine that by turning the cup in one direction the valve will be opened and in the other direction it will be 20 closed. In the form shown in Figs. 1 and 2 by turning the cup toward the right the valve will be closed and by turning it toward the left it will be opened, thus drawing the valve when the cup is closed against 25 the seat, while in the form shown in Figs. 4 and 5 by turning the cup to the right it will be opened and by turning it to the left it will be closed, the turning of the cup to the left forcing the valve to its seat.
- 30 35 By means of the foregoing improvement I am able to provide a much smaller cup having a larger shiftable fluid receiving chamber than has heretofore been possible in constructions of this kind, since it will be observed that the body member comprises a projecting threaded stem adapted to fit into the cylinder of the engine while the cup member likewise comprises a projecting threaded stem fitting into the body member, 40 which stem is utilized by chambering it to increase the capacity of the cup while permitting the size or diameter of the article to be materially reduced. Thus the cup member has a chamber of three different diameters all located above the perforated bottom wall thereof, so that when the fluid passes through the perforations in the bottom wall of the cup member it passes directly into the 45 passage 23' of the body member, thus as hereinbefore stated enabling the cup member to be made together with its bottom wall of an integral construction.

50 As a result of this improved construction, it will be observed that the exteriorly threaded stems of the fluid cup member and of the body member are of substantially the same diameter while the extended chamber portion 17 of the cup member is shown of greater diameter than the passage through 55 the body stem, which thus enables the for-

mation of an uninterrupted chamber in the cup member of very much increased capacity.

It is to be understood that by describing in detail herein any particular form, structure or arrangement, it is not intended to limit the invention beyond the terms of the several claims or the requirements of the prior art.

Having thus explained the nature of my 75 said invention and described a way of constructing and using the same, although without attempting to set forth all of the forms in which it may be made, or all of the modes of its use, I claim:

1. A priming device comprising a body member having an exteriorly threaded hollow stem provided with a valve seat and an enlarged interiorly threaded chamber of materially greater interior diameter than the 85 interior diameter of said hollow stem, a shiftable fluid-receiving chamber having an extended chamber portion exteriorly threaded into the chamber of the body and having an interior diameter as great as the interior 90 diameter of the hollow stem, thereby materially increasing the capacity of the fluid-receiving chamber, and provided with a depending valve stem having a valve 95 co-operating with said valve seat.

2. A priming device comprising a body member having an exteriorly threaded hollow stem provided with a valve seat at its lower end, and an enlarged interiorly threaded chamber of materially greater interior diameter than the interior diameter of said hollow stem, a shiftable fluid-receiving chamber having an extended chamber portion exteriorly threaded into the chamber of the body and having an interior 100 diameter as great as the interior of the hollow stem, thereby materially increasing the capacity of the fluid-receiving chamber, and provided with a depending valve stem having a valve 105 co-operating with said valve seat.

3. A priming device comprising a body member having an exteriorly threaded hollow stem provided with a valve seat, and an enlarged interiorly threaded chamber of

materially greater interior diameter than 115 the interior diameter of said hollow stem, a shiftable fluid-receiving chamber having an extended chamber portion exteriorly threaded into the chamber of the body and having an interior diameter as great as the interior diameter of the hollow stem, thereby 120 materially increasing the capacity of the fluid-receiving chamber and provided with a depending valve stem having a valve co-operating with said valve seat and opening 125 in the direction of the flow of the fluid.

4. A priming device comprising a body member having an exteriorly threaded hollow stem provided with a valve seat, and an enlarged interiorly threaded chamber of 130

materially greater interior diameter than the interior diameter of said hollow stem, a shiftable fluid-receiving chamber having an extended chamber portion exteriorly threaded into the chamber of the body and having an interior diameter as great as the interior diameter of the hollow stem, thereby materially increasing the capacity of the fluid-receiving chamber and provided with a perforated bottom wall, and a depending valve stem connected with said bottom wall and having a valve cooperating with said valve seat.

5. A priming device comprising a body member having an exteriorly threaded hollow stem provided with a valve seat, and an enlarged interiorly threaded chamber of

materially greater interior diameter than the interior diameter of said hollow stem, a shiftable fluid-receiving chamber having an 20 extended chamber portion exteriorly threaded into the chamber of the body and having an interior diameter as great as the interior diameter of the hollow stem, thereby materially increasing the capacity of the fluid- 25 receiving chamber and provided with a perforated bottom wall, and a depending valve stem connected with said bottom wall and having a valve cooperating with said valve seat, said valve opening in the direction of 30 the flow of the fluid.

Signed at Cleveland Ohio this 14th day
of July, 1924.

OSCAR AUGUST SMITH.
